US00D633616S

(12) **United States Design Patent**
Lafauci et al.

(10) **Patent No.:** **US D633,616 S**
(45) **Date of Patent:** **** Mar. 1, 2011**

(54) **SCALPEL**

(75) Inventors: **Michael Lafauci**, Center Moriches, NY (US); **Scott Berlin**, Bay Shore, NY (US)

(73) Assignee: **Brolex, LLC**, Bay Shores, NY (US)

(**) Term: **14 Years**

(21) Appl. No.: **29/364,320**

(22) Filed: **Jun. 22, 2010**

(51) **LOC (9) Cl.** **24-02**

(52) **U.S. Cl.** **D24/147**

(58) **Field of Classification Search** **D24/30, D24/28, 146, 147, 133; D8/98, 99, 102; 30/339, 294, 2, 340, 283, 289; 606/167**

See application file for complete search history.
